C. RIST

BURGLAR ALARM

Filed Jan. 19. 1921

UNITED STATES PATENT OFFICE.

CONRAD RIST, OF LOS ANGELES, CALIFORNIA.

BURGLAR ALARM.

Application filed January 19, 1921. Serial No. 538,358.

To all whom it may concern:

Be it known that I, CONRAD RIST, a citizen of the United States of America, residing at the city and county of Los Angeles, in the State of California, have invented certain new and useful Improvements in Burglar Alarms, of which the following is a specification, reference being had to the accompanying drawings.

10 This invention relates to improvements in burglar-alarms, and particularly to improvements in burglar-alarms that are electrically-operated. An object of this invention is to provide an electrically-operated burglar-alarm which will prove simple in construction, comparatively cheap in manufacture and low in cost of installation and repair, and efficient, reliable, durable and sensitive in operation and use.

15 Another object of this invention is to provide an electrically-operated burglar-alarm which may be readily placed in operative position and quickly removed therefrom when it is no longer needed for use.

20 In the drawings illustrating the principle of this invention and the best mode now known to me of applying that principle, Fig. 1 is an edge view or side elevation of the burglar-alarm, the battery and alarm-bell being shown conventionally; Fig. 2 is a front elevation or face view; and Fig. 3 illustrates the base or body member fitted in place in the lock-plate of a door.

25 From one end of the base-piece or body-member *a*, there is punched out a laterally-projecting lug *a'*; and, from the same face *a''* of the base-piece *a*, there projects, at the other end thereof, a contact-stud *b* formed with a hole *b'* for the reception of one end 30 of the conductor *d*, the other end of which is electrically connected with one pole *c'* of the battery *e*. The contact-stud *b* is formed with a socket into which is screwed the contact-screw *c*, by means of which the conductor *d* is held in place. The opposite face *a''* of the base-piece *a* is formed with a series 35 of teeth *f*, with which engages the toe-end *g* of a locking-pawl *h* which is pivotally mounted between a pair of ears *i* that project from the middle of the outer face *j'* of an adjustable slide *j* mounted on the base-piece *a* (see Figs. 1 and 2). The other end 40 of the pawl or catch *h* is formed with a head or button *h'* and is forced outwardly or away from the base-piece *a* by means of a helical spring *h''*, whereby the toe *g* is held

in engagement with the teeth *f* and the slideable contact-carrier *j* is held in its adjusted position on the base-piece *a*. One end of the contact-carrying slide *j* is bent outwardly at 45 right angles to the body thereof and away from the base-piece *a* to form a seat or support *j''* upon which is secured, by the fastening device *k*, a contact-stud *m* having a hole *m'* for the reception of one end of a conductor *n*, the other end of which is electrically connected with an alarm-bell *p*. By means of a contact-screw *o*, the conductor *n* is secured in place in the contact-stud *m*. By means of a conductor *q*, the alarm-bell *p* 50 is electrically connected with the other pole *e''* of the battery *e*. The fastening device *k* (which, as shown in Fig. 2, is a small screw-bolt having a nut engaging its threaded end) is insulated from the seat or support *j''* by 55 the insulation *j'*, as is also the contact-pin *r* that projects from the base *m''* of the contact-stud *m*. Secured to a contact-post *s* by means of the screw *s'*, is a leaf-spring *t*, which acts as a circuit make-and-break; that 60 is, when the contact-spring *t* is pressed against the contact-pin *r*, current will flow from the positive pole *e'* of the battery *e* through the conductor *d*, post *b*, base-piece *a*, slide *j*, stud *s*, spring *t*, pin *r*, base *m''*, 65 post *m*, conductor *n*, alarm-bell *p*, and conductor *q* to the negative pole *e''* of the battery *e*; and, due to the passage of the current through the alarm-bell *p*, the same will be 70 rung.

75 The base-piece *a* is made of comparatively thin metal. As illustrated in Fig. 3, the end of the base piece *a* that is formed with the lug *a'* is placed against the lock-plate *u* with the lug *a'* projecting into the lower hole *u'* of the lock-plate *u* (see also Fig. 1). By closing the door *v* (which may be closed since the base-piece is so thin), the base-piece *a* is held in the horizontal position 80 illustrated in Fig. 3 and projects inwardly 85 into the room. The contact-carrying slide *j* is now slipped over the free inner end of the base-piece *a* and is pushed therealong towards the door, until the contact-spring *t* is very close to the door *v*, whereupon the toe *g* of the catch or dog *h* is 90 allowed to be pressed, by the helical spring *h''*, into engagement with the toothed rack *f* and locks the slide *j* in its adjusted position. Should the door *v* be forced inwardly 95 with the parts in the relative positions shown in Fig. 1, the door *v* will push the 100

105

110

contact-spring *t* against the contact-pin *r* and will thereby close the circuit, whereupon the current will be caused to flow through the signal-bell *p*, operating the same as has 5 hereinbefore been described.

In accordance with the patent statutes, I have described and shown the preferred embodiment of this invention herein; but it will be readily understood, by all skilled 10 in this art, that changes may be made without departing from this invention. For example, a step-down transformer or any other source of low-voltage current may be substituted for the battery *e*. Again, a buzzer, 15 or any other electrically-operated signalling device capable of giving forth signals of sufficient intensity or loudness, may be used in place of the alarm-bell *p*, which is shown and intended to be understood merely 20 as one form of several suitable alarms.

I claim:

1. A burglar-alarm including a thin contact-stud-carrying base-plate arranged to be fitted in its operative position between a 25 door and the frame thereof and of such thinness as to permit the free opening and closing of the door with the base-plate in its operative position; a contact-stud-carrying slide mounted on the base-plate and 30 adjustable therealong into the path of the door; means for retaining the slide in its adjusted position; and a circuit make-and-break device mounted on the slide and operable by the door when the same is opened. 35

2. A burglar-alarm including a thin contact-stud-carrying base-plate arranged to be fitted in its operative position between a

door and the frame thereof and of such thinness as to permit the free opening and closing of the door with the base-plate in 40 its operative position and formed with a lug for insertion into a lock-plate hole for maintaining the base-plate in operative position; a contact-stud-carrying slide mounted 45 on the base-plate and adjustable therealong into the path of the door; means for retaining the slide in its adjusted position on the base-plate; and a circuit make-and-break device mounted on the slide and operable by the door when the same is opened. 50

3. A burglar-alarm including a thin base-plate arranged to be fitted, in its operative position, between a door and the frame thereof and of such thinness as to permit the free opening and closing of the door 55 with the base-plate in its operative position and having one of its faces serrated; a contact-stud-carrying slide mounted on the base-plate and adjustable therealong into the 60 path of the door; a catch carried by the slide and arranged to engage the serrated face of the base-plate and to hold the slide in its adjusted position on the base-plate; and a circuit make-and-break device mounted on the slide and operable by the door 65 when the same is opened.

Signed in the presence of the two undersigned witnesses, at the city and county of Los Angeles, in the State of California, this eleventh day of January, 1921.

CONRAD RIST.
